UNITED STATES PATENT OFFICE.

JOHN J. WARNS, OF WENTWORTH, SOUTH DAKOTA.

GATE-LATCH.

991,119.

Specification of Letters Patent.

Patented May 2, 1911.

Application filed September 13, 1910. Serial No. 581,882.

To all whom it may concern:

Be it known that I, JOHN J. WARNS, citizen of the United States, residing at Wentworth, in the county of Lake and State of 5 South Dakota, have invented certain new and useful Improvements in Gate-Latches, of which the following is a specification.

The present invention comprehends certain new and useful improvements in gate 10 latches, and the invention has for its object an improved device of this character which is quite simple, durable and efficient in construction and which is designed particularly for use in connection with a double- 15 swinging gate and is arranged to hold the gate securely in closed position, the latch being susceptible of being conveniently operated from either desired side of the gate so as to permit the gate to be pushed open 20 from said side thereof.

A further object of the invention is a gate latch which retains the gate in closed position when the same is slammed to, and thus prevents the gate from swinging 25 through the gateway or from rebounding.

With these and other objects in view that will more fully appear as the description proceeds, the invention consists in certain constructions and arrangements of the 30 parts that I shall hereinafter fully describe and then point out the novel features of in the appended claims.

For a full understanding of the invention and the merits thereof and also to acquire a 35 knowledge of the details of construction, reference is to be had to the following description and accompanying drawing, in which:

Figure 1 is a perspective view illustrating 40 the application of my improved gate latch; Fig. 2 is a front elevation of the latch, the keeper being shown in section in position between the detents; Fig. 3 is a horizontal section of the gate and latch-post showing the 45 latch in top plan view; and, Fig. 4 is a fragmentary perspective view of one end of the base plate illustrating in detail the form of the stop.

Corresponding and like parts are referred 50 to in the following description and indicated in all the views of the drawing by the same reference characters.

My improved gate latch includes an elongated base plate 1 which is formed with a plurality of apertures 2 for the reception 55 of screws or other suitable fastening devices by means of which it is attached in a substantially horizontal position to the inner face of the latch-post A of the fence. The base plate is provided in proximity to its ends with outstanding studs 3 on which are pivotally mounted a pair of latch bars that are designated 4 and 4^a respectively, each latch bar having its pivotal point located intermediate of its ends. The latch bars 60 normally assume substantially horizontal positions so as to lie in longitudinal alinement.

The forward or adjacent end portions of the latch bars lie side by side or lap each other, and are formed with terminal detent 70 teeth 5. The teeth depend from the latch bars as shown. The forward end portion of the latch bar 4 is offset laterally just behind its detent tooth, as indicated at 6, in order to support said tooth in spaced relation to the base plate and in a plane substantially parallel thereto. The forward end portion of the latch bar 4^a is offset laterally, as indicated at 7, away from the base plate and at a point in proximity to its pivot so 80 as to extend outside of the offset terminal of the latch bar 4. The detent tooth 5 of the latch bar 4^a is offset toward the latch bar 4 at a point opposite the offset portion 6, as indicated at 8. The latch bar 4^a is thus 85 bowed outwardly to accommodate the offset terminal of the latch bar 4, and the detent teeth 5 are caused to operate in the same plane.

It is to be particularly observed that in 90 the normal positions of the latch bars, the detent teeth are spaced apart longitudinally, the detent tooth of each latch bar occupying a position between the tooth of the other latch bar and the pivotal point of the last-named latch bar. The adjacent or opposing edges of the teeth are substantially abrupt and constitute abutments, while the remote edges of the teeth are beveled, as indicated at 9, for a purpose to be hereinafter disclosed.

The rear or tail ends of the latch bars form operating handles 10 and are preferably relatively wide and project beyond the

respective ends of the base plate and beyond the adjacent sides of the latch-post A so as to be conveniently accessible from either desired side of the fence. The forward ends of 5 the latch bars are considerably heavier than the handles and tend to swing downwardly by gravity. In order to limit the pivotal movement of the latch bars the stops 11 are extended outwardly from the base plate 10 above the pivotal points of the respective bars. Each stop is of angular formation and has its vertex disposed substantially in vertical alignment with the adjacent pivot. One portion of the stop is disposed sub- 15 stantially horizontally and is arranged to bear against the upper edge of the tail portions of the latch bar in order to limit the dropping movement of the latch bar by gravity and to normally maintain the latch 20 bar in a substantially horizontal position. The other portion of the stop extends obliquely upwardly and provides an abutment for the forward end portion of the latch bar to limit the upward movement thereof.

25 The keeper is carried by a double-swinging gate B, and consists essentially of a pin 12 which projects from the latch-style of the gate at a suitable point so as to be engaged by the latch on the post A. The 30 pin is formed with a laterally enlarged base 13 which has an extended bearing on the latch-style in order to brace the pin and prevent its accidental displacement. A threaded stem 14 is extended inwardly from 35 the base and passes through the latch-style and is engaged by a nut 15, whereby to secure the keeper to the gate. The inner face of the base is preferably concave in order to fit snugly to the tubular latch-style 40 of the metal gate. When the keeper is employed on a wooden latch-style having a flat face, the side edge portions of the base are embedded in said latch-style upon the tightening of the nut 15 and thus assist in securing 45 the device in place. The keeper is, therefore, capable of being applied to both metal or wooden gates.

In practice, the keeper pin 12 is confined 50 between the detent teeth 5, whereby to effectually retain the gate in closed position against any swinging movement in either direction. To open the gate, the operator depresses the handle 10 on one side of the fence and thus rocks the corresponding latch 55 bar to lift its detent tooth 5 sufficiently to clear the pin 12 of the keeper. The gate may then be pushed open from the aforesaid side of the fence. As soon as the handle is released the latch-bar is automatically re- 60 turned to its normal position by gravity. It is not necessary to carefully close the gate after the operator has passed through the gateway, but the gate may be slammed to. As the gate swings to closed position, the 65 pin 12 rides upon the beveled edge 9 of the

adjacent detent tooth 5 and rocks the latch-bar to lift said tooth out of its path. However, the pin is caught by the other detent tooth and the gate is thus prevented from swinging entirely through the gateway. 70 The lifted tooth falls immediately by gravity and engages the pin to insure against the possible rebounding of the gate. As the teeth are directly opposite each other in their normal positions they engage the pin 75 quite effectively, and have no tendency to bend the pin. The advantage of having the detent teeth operate in a plane spaced from the base plate, resides in the fact that the teeth are rendered capable of embracing pins 80 of slightly different lengths, and hence the positive action of the latch is insured.

From the foregoing description in connection with the accompanying drawing, it will be apparent that I have provided an improved gate latch which is thoroughly practical and reliable in operation, which may be operated from either side of the gate, and which permits the gate to be pushed open 85 from the side from which it is operated, 90 thereby obviating the necessity of pulling the gate open as is required with some of the devices heretofore employed for this purpose. The latch consists of comparatively few parts and is adapted to be easily 95 and cheaply manufactured.

The base plate 1 preferably comprises upper and lower attaching flanges 16 and an intermediate raised portion 17 to which the latch bars are pivotally connected. The detent teeth 5 normally depend below the raised portion so as to engage the keeper pin that is movable thereunder. By having the central portion of the base plate raised, the detent teeth are rendered capable of engaging the pin in closer proximity to the base 13 thereto, whereby to obviate the liability of the pin slipping by the latch in event of the sagging of the gate or a like contingency. The stops 11 are struck from the raised portion, 105 as shown.

Having thus described the invention, what is claimed is:

1. A device of the character described including a base, a latch pivotally connected 115 to the base and provided at one end with an angularly disposed detent, said latch being offset laterally intermediate of its pivot and the detent, and a second latch pivotally connected to the base and provided at one end with an angularly disposed detent, the second latch being bowed laterally between its pivot and its detent to receive the offset terminal of the first latch, the latches normally lapping each other with each detent positioned between the other detent and the pivotal point of the other latch. 120

2. A device of the character described including a base, a latch pivoted at an intermediate point to the base, the latch being 130

formed at one end with a detent and being provided at its other end with a handle, and a stop outstanding from the base on one side of the latch, the stop being in the form of 5 an obtuse angle with its vertex disposed in substantially transverse alinement with the pivot of the latch.

In testimony whereof, I affix my signature in presence of two witnesses.
